[57] CLAIM

The ornamental design for a lower front facing surface of a front end of an automobile, as shown and described.

DESCRIPTION

FIG. 1 is a front view of the lower front facing surface of a front end of an automobile according to our novel design; and,

FIG. 2 is a perspective right side view of the lower front facing surface of a front end of an automobile according to our novel design.

The portions with dashed line borders are for illustrating the surrounding environment and do not form part of the design being claimed.
